UNITED STATES PATENT OFFICE.

MAURICE J. NOVOSON AND JAMES B. HILL, OF ST. LOUIS, MISSOURI, ASSIGNEES TO
JAMES B. HILL HAT COMPANY, OF ST. LOUIS, MISSOURI, A CORPORATION OF
MISSOURI.

CAP.

1,123,354.

Specification of Letters Patent.

Patented Jan. 5, 1915.

Application filed June 13, 1914. Serial No. 844,967.

To all whom it may concern:

Be it known that we, MAURICE J. Novoson and JAMES B. HILL, citizens of the United States, residing at the city of St. Louis, State of Missouri, have jointly invented a certain new and useful Improvement in Caps, of which the following is a specification, reference being had to the accompanying drawing, forming a part 10 thereof.

This invention relates to a certain new and useful improvement in caps or head-wear, the objects of our present invention being to provide a cap adapted to yieldingly 15 fit, within certain limits, heads of various sizes; to provide a cap not only adapted to normally furnish as an ordinary cap the usual top-covering for the head, but to also abnormally furnish a covering, and serve as 20 a protector, for the ears and back of the head; to provide a cap of the kind described with not only readily adjustable, but also readily detachable and renewable, resilient size-reducing members; to provide a cap of 25 the kind described which may be economically manufactured and which, whether in normal or abnormal condition, will present a neat and attractive appearance; and to improve generally upon caps of the kind described.

With the above and other objects in view, our invention resides in certain novel features of form, construction, arrangement, and combination of parts, all as will herein- 35 after be described and afterward pointed out in the claims.

In the accompanying drawings, Figure 1 is an elevational view of our new cap as when in normal condition upon the head of a wearer; Fig. 2 is an enlarged fragmentary view, partly broken away, of the band of the cap in fully extended condition; Fig. 3 is a longitudinal sectional view on the line 3—3, Fig. 2; Fig. 4 is an enlarged fragmentary 45 view of the band of the cap in fully resiliently reduced condition; Fig. 5 is a longitudinal sectional view on the line 5—5, Fig. 4; Fig. 6 is a transverse sectional view on the line 6—6, Fig. 2; Fig. 7 is a similar 50 view on the line 7—7, Fig. 2; Fig. 8 is a detail fragmentary view of the band of the cap, showing one of its resilient size-reducing members in an adjusted position; and Fig. 9 is a longitudinal sectional view on 55 the line 9—9, Fig. 8.

As seen in said drawing, in which like reference characters refer to like parts throughout the several views, our new cap comprises a body-portion 1, a band 2, and a vizor 3, which latter member may be of any usual or approved form and sewed or otherwise fixed to body-portion 1 and band 2 in any suitable manner.

Body-portion 1, which may be of any suitable flexible material, is preferably at 65 its edge inturned or folded upon itself, as at 1^a, the marginal portion 4 of body-portion 1 forming with a strip or band 5 also of suitable flexible material, fixed upon the inner surface of said marginal portion 4 70 preferably by longitudinal rows of thread stitches or the like running along its opposite side edges, band 2.

Band 2 of the cap is cut or formed and designed to fit any certain predetermined 75 size of head, say, for instance, seven and one-half, the major portion of body-portion 1 being also loosely cut or made to provide a considerable fullness of material which is adapted to normally, as seen in Fig. 80 1, exteriorly overlie or overhang band 2 in attractive folds, as at 6, 7, and 8.

At each side of the cap, preferably adjacent the opposite ends of vizor 3, members 4 and 5 of band 2 are also sewed together by 85 pairs of spaced transverse thread stitches 9—9, the portions of band 2 therebetween forming what might be called casings 10, band-portion 4 adjacent said stitches 9—9 being transversely cut or slitted, as at 11—90 11, to provide openings into the casings 10, as seen clearly in Figs. 2 and 4. Centrally in each of the casings 10, band members 4 and 5 are again sewed together by a pair of spaced-apart short longitudinal rows of 95 thread stitches 12—12, a central longitudinal passage, as at 13, through each of the casings 10 in alignment with its openings 11—11 being thereby provided.

Fixed on band 2 adjacent, and in alignment with the casing-openings 11—11, are headed buttons or the like 14—14, and extending loosely through each of the casings 10 and its said passage 13 and detachably engaging with said buttons 14—14, is an 100 elongated endless loop 15 of suitable elastic material adapted to yieldingly reduce the size of band 2 so that the same may also tightly fit within certain limits heads of a different and smaller size than the prede- 110

terminated size which band 2, when fully extended, is designed to fit.

Elastic loops 15 extending loosely and freely through said band-casings 10 and engaging, as described, with fixed buttons 14—14, band 2 will readily yield to easily and perfectly fit heads of various sizes within the limits of the particular cap, the passages 13 in casings 10 not only preventing lateral movement of the elastic loops 15 relatively to band-casings 10, but also to a certain extent centrally stiffening the band-casings 10 so that, when the cap and said elastic loops are in either normal unstretched or partly stretched condition, the band-casings 10 to each side or end of the passages 13 will fold inwardly upon themselves in oppositely-disposed neat attractive folds, as at 16—16, as seen clearly in Figs. 1 and 4.

20 The elastic loops 15 being readily detachable from buttons 14 and removable from casings 10, it will be clearly seen that, should the same become worn or lose their elasticity, the same may be readily and quickly renewed. It will also be evident that, should the elastic loops 15 become only slightly worn, the tension thereof and consequently the fit of the cap may be adjusted by merely wrapping or winding the same 25 around the buttons 14, as seen clearly in Fig. 8. Furthermore, it will be evident that, due to the fullness of body 1 and the expansibility of band 2, the cap may, whenever required or desired, as, for instance, 30 in wintry or stormy weather, be pulled down over the head and into abnormal condition, as shown by dotted lines in Fig. 1, to provide, in addition to a top-covering for the head, a covering or protector for the ears 35 and the back of the head.

We are aware that minor changes in the form, arrangement, construction, and combination of the several parts of our cap may be made and substituted for those herein shown and described without departing from the nature and spirit of our invention.

Having thus described our invention, what we claim and desire to secure by Letters Patent is:

40 1. In a cap, a flexible body-portion, a flexible band, said body-portion and band being adapted and designed to fit a predetermined size of head and said band including an open-ended casing, buttons fixed on said band adjacent to, and in alinement with, the open ends of said casing, and an elastic member extending longitudinally, through said casing and engaging with said buttons, said elastic member being adapted to 45 resiliently reduce the size of said band to yieldingly fit sizes of head smaller than said predetermined size; substantially as described.

2. In a cap, a flexible body-portion, a flexible band, said body-portion and band being

adapted and designed to fit a predetermined size of head and said band including a plurality of open-ended casings, buttons fixed on said band adjacent to, and in alinement with, the open ends of each of said casings, and elastic members extending longitudinally through said casings and engaging with said buttons, said elastic members being adapted to resiliently reduce the size of said band to yieldingly fit sizes of head smaller than said predetermined size; substantially as described.

3. In a cap, a flexible body-portion, a flexible band, said body-portion and band being adapted and designed to fit a predetermined size of head and said band including a plurality of open-ended casings, buttons fixed on said band adjacent to, and in alinement with, the open ends of said casings, and endless elastic loops extending loosely through said casings and detachably engaging with said buttons, said elastic loops being adapted to resiliently reduce the size of said band to yieldingly fit sizes of head smaller than said predetermined size; substantially as described.

4. In a cap, a flexible body-portion, a flexible band, said body-portion and said band being adapted and designed to fit a predetermined size of head and said band including a plurality of open-ended casings, spaced rows of thread stitches in said band extending longitudinally and centrally of said casings, said rows of stitches providing central longitudinal passages in said casings, buttons fixed on said band adjacent the open ends of said casings and in alinement with said central passages thereof, and endless elastic loops extending lengthwise through said casings and their said passages and detachably engaging with said buttons, said elastic loops being adapted to resiliently reduce the size of said band to yieldingly fit sizes of head smaller than said predetermined size and said band at said casings to each side of said passages therethrough folding upon itself in oppositely-disposed folds when said elastic loops are in normal unstretched conditions; substantially as described.

5. In a cap, a flexible body-portion, a flexible strip stitched longitudinally to said body-portion at its margin and forming therewith a flexible band, said body-portion and said band being adapted and designed to fit a predetermined size of head and said body-portion normally folding over upon and overhanging said band, spaced rows of thread stitches extending transversely of and through said band, said band being transversely slitted adjacent said transverse rows of thread stitches, spaced rows of thread stitches extending longitudinally of and through said band intermediate said transverse slits, said latter rows of thread

stitches providing longitudinal passages in said band, buttons fixed on said band adjacent said slits and in alignment with said passages, and endless elastic loops extending longitudinally through said passages and detachably engaging with said buttons, said elastic loops being adapted to resiliently reduce the size of said band to yieldingly fit sizes of head smaller than said predetermined size and said band to each side of said passages therethrough folding upon itself

in oppositely-disposed folds when said elastic loops are in normal unstretched condition; substantially as described.

In testimony whereof, we have signed our 15 names to this specification, in the presence of two subscribing witnesses.

MAURICE J. NOVOSON.
JAMES B. HILL.
